HEEL ATTACHING MACHINE

John T. Lancaster, Newtonville, Mass., assignor
to United Shoe Machinery Corporation, Pater-
son, N. J., a corporation of New Jersey

Application October 29, 1936, Serial No. 108,237

8 Claims. (Cl. 12—1)

This invention relates to heel attaching machines and particularly to machines for attaching heels to shoes by means of an adhesive, such as cement.

5 The object of the invention is to provide an improved machine by which heels may be cement attached to shoes rapidly and with greater uniformity and strength than heretofore. To this end there is provided, in the illustrated embodiment of the invention, a multi-station machine at one station of which is a mechanism for molding the heel seat of a shoe to conform exactly to the cup of the heel, at another station the heel is applied to the shoe and the shoe and heel are subjected to clamping pressure, while other stations provide opportunity for other operations, hand or otherwise, to be performed upon the shoe.

10 I prefer to jack and clamp each shoe separately in an individual jack or clamp of an unconnected series and in order to secure maximum flexibility in operation the jacks may be arranged to travel around a circular or other orbital track and stop automatically at definite stations where operations may be performed upon the shoes.

15 In the cement attachment of a heel to a shoe it is important to the production of a strong bond that the heel be pressed tightly against the heel seat of the shoe and kept under fairly heavy pressure until the cement has set. Experience has shown that after the initial application of pressure the shoe materials and, to some extent, the cement continue to yield gradually and when the work is held in a fixed clamp for a time considerable of the pressure is sometimes lost, with the result that the joint is not as strong as it might be whereas if the contraction of the materials is followed up by the pressure applying apparatus so that the pressure is maintained at the initial high value, or even somewhat increased, a joint of maximum strength is obtained.

20 A feature of the invention, accordingly, consists in the provision of follow-up means for restoring or increasing the pressure from time to time after the initial application thereof.

25 As illustrated herein, the pressure is applied by screw and automatic means are provided for further turning the pressure screw from time to time as the jack proceeds around the track after leaving the station where the initial pressure is applied.

30 These and other features and details of the invention will be better understood and appreciated from reading the following description of

one practical embodiment thereof in connection with the accompanying drawings, in which

Fig. 1 is a view in front elevation of a heel attaching machine with certain parts broken away to reveal details of internal structure;

Fig. 2 is a plan view of the machine;

Fig. 3 is a view in elevation and section upon the line III—III of Fig. 2, illustrating certain details at the center of the machine;

Fig. 4 is a side view, partly in section, of one 10 of the shoe and heel clamping jacks and its carrier;

Fig. 5 is a front view of the jack;

Fig. 6 is a plan view of the jack carrier;

Fig. 7 shows a detail of the mechanism for 15 connecting the jack carrier to and disconnecting it from the driving member;

Fig. 8 is a plan view partly in section upon the line VIII—VIII of Fig. 4;

Fig. 9 is a vertical section upon the line IX—IX 20 of Fig. 5, showing the structure of the last and last support, and

Fig. 10 is a plan view of the heel seat portion of the last.

25 In the drawings, 12 indicates a casting comprising the base of the machine and providing a bearing for a vertical hollow shaft 14 to the lower end of which is keyed a worm gear 16 meshing with a worm 18 fixed upon a horizontal shaft 20, which may be continuously driven from any 30 suitable source of power in order to rotate the hollow vertical shaft 14.

35 Keyed to the upper end of the hollow shaft 14 is the hub 22 of a wheel having five radial spokes 24 and a solid rim 26 to the periphery of 35 which are secured at suitable intervals by means of screws 28 a series of jack driving dogs 30, as shown in Figs. 2 and 6.

40 Extending through the hollow shaft 14 is a stationary vertical post 32 the lower end of which 40 is secured by a set screw 34 in a bracket 36 supported by the base 12 and the upper end of which has secured to it by a set screw 38 the hub portion 40 of a stationary spider having three arms 42, 44, 46, the outer end of each of which provides a flattened side face 48 for engagement by 45 a portion of the pressure applying mechanism to be described later.

45 Four radial arms 50 bolted to the sides of the upper portion of the base 12 serve to support a 50 circular track consisting of inner and outer concentric rails 52 and 54, respectively, upon which a series of unconnected individual shoe and heel clamping jacks travel from station to station. These jacks are identical in construction and 55

indeterminate in number, according to the size of the machine and the length of time during which it is required that the work be held under pressure by reason of the number and nature of the operations to be performed on it and the setting characteristics of the cement or cements used.

Each jack is supported upon a carrier comprising a table 56 which is drilled horizontally to receive anti-friction rolls 58 which run upon the tops of the track rails 52, 54 and are maintained in their proper positions in the table 56 by screws 60 the points of which engage in grooves 62 in the rolls (Figs. 4 and 6).

15 Other, vertical, anti-friction rolls 64 which fit in the space between the track rails are held to the under side of the table 56 by shouldered bolts 66 threaded into the table at 68 (see Fig. 4) and having enlarged heads 70 which serve to hold 20 the carrier down to the track.

A jack base 72 rests upon and is supported by the carrier table 56 upon which it is permitted to swivel around a vertical axis by a shouldered bolt 74 passing loosely through the table 56 and 25 threaded into the jack base at 76, as shown in Fig. 4. A tapered detent plug 78, urged downward by a spring 80 into a hole 82 in the upper face of a bracket 84 which projects forward from the table 56, provides for locking the jack base 30 against swivel movement upon the table but may be lifted against the tension of the spring by a handle 86 to permit the jack to be swung around through any desired horizontal angle.

35 Slidably mounted in the base 72 is a plate 88, held down by gibbs 90 and adjustable forward or rearward of the jack base by means of a screw 92 which is threaded into said base and is provided with a collar 94 bearing against the rear face of a forwardly and downwardly projecting portion 96 of the sliding plate 88. The portion 40 of the screw 92 in front of the collar 94 is smooth and passes loosely through a hole in the member 96, having secured to its front end a hand wheel 98 the hub of which bears against the front face 45 of the member 96, thus providing for adjustment of the slide 88 and the last support carried thereby.

50 Arising from the slide 88 are two curved arms 100, 102, in the upper ends of which are fastened horizontal stub shafts 104, 106 upon which is 55 hung for free swinging movement, about an axis transverse to the jack, a cradle 108. The floor portion of the cradle 108 is formed to provide a last support 110 upon which the cone of a last 60 112 may be placed, a last pin 114 being screwed into the last support 110 and adapted to enter the last thimble 116 to position the last and prevent it from shifting horizontally upon the support 110, and the axis of the shafts 104, 106 is so positioned that it will substantially pass through the heel seat of a lasted shoe upon the said support.

65 Extending rearward from the last support 110 is an arm 118 to the rear end of which is pivoted at 120 an upwardly extending yoke 122, between the upper ends of which is mounted a back gage 124 having a lining of leather, rubber or the like 126. The back gage 124 is positioned to engage the back of a shoe 128 upon the last 112 and project upward past the shoe bottom to provide 70 positive positioning means for the back of the heel 130 to be attached to the shoe, as shown in Figs. 4 and 9.

In order to accommodate lasts having differently positioned pin holes the yoke 122 and the 75 back gage 124 are adjustable about the pivot 120.

To this end, a threaded stud 132, extending laterally from the yoke 122, passes through a curved slot 134 in a rearwardly projecting portion 136 of the left hand side of the cradle 108 and a threaded nut 138 having a handle 140 is adapted 5 to be tightened upon the stud 132 to clamp the yoke 122 firmly to the said cradle portion 136, making the back gage 124 rigid with the last support. The gage 124 thus constitutes a combination gage for the rear of the shoe and the 10 rear of the heel, insuring the placing of the heel so that its back face will form a smooth continuation of the line of the back face of the shoe.

In order to provide pressure for clamping the heel 130 upon the shoe 128 a presser foot 142 is 15 pivotally mounted upon a pin 144 carried by a vertically slidable bar 146. The bar 146 is guided for free vertical movement in a hole 148 formed in the upper portion of an upright 150 which is integral with the jack base 72. In order to prevent the pin 144 and the presser foot 142 from swinging around the axis of the bar 146 the pin is fastened by a set screw 152 in the lower end of a vertical rod 154 which passes loosely through the center of a hollow pressure screw 156 to the 20 upper end of which is secured by a set screw 158 a hand wheel 160.

Interposed between a collar 162 upon the lower end of the rod 154 and the lower end of the pressure screw 156 is a stiff spring 164 which is 30 sufficiently heavy to sustain the entire pressure to be applied to the work. A collar 166 threaded upon the upper end of the rod 154 and bearing upon the upper face of the hub of the hand wheel 160 provides for adjusting the tension of the 35 spring 164.

The pressure screw 156 is freely slidable vertically through a guide opening 168 formed in the overhanging portion of the upright 150 and its threads are engaged by a worm gear 170 fixed 40 upon a horizontal shaft 172 which is journaled in bearings 174, 176 formed in the said overhanging portion of the upright 150. A hand lever 178 is keyed upon the shaft 172 and constitutes manually operable means for turning the worm gear 45 170 and consequently moving vertically the pressure screw 156 engaged therewith.

In order to lock the lever 178 against movement in a direction to permit release of the pressure there is provided a sliding pawl 180 drawn by a 50 spring 182 into engagement with a stationary ratchet segment 184 secured to the side of the overhanging portion of the upright 150. A pin 185 projecting from the side of the pawl permits it readily to be withdrawn from the ratchet segment to allow the pressure to be released.

It will now be understood that the manually operable lever 178 may be employed to move the pressure screw and the presser foot 142 rapidly downward to apply preliminary pressure to the 60 heel and shoe, the lever being automatically locked by the pawl 180, and then the hand wheel 160 may be utilized to turn the screw to provide increased final pressure, the locked worm gear 170 constituting a stationary nut for the screw 65 and the pressure being applied through the heavy spring 164 which may yield slightly and so measure the pressure as to facilitate the application of substantially the same pressure to various pieces of work.

70 For the purpose of controlling the connection of the jack to the driving member 26 and its disconnection therefrom there is provided in the jack carrier 56 a slidably latch bar 186, best shown in Figs. 6 and 7, which is normally urged rear- 75

ward by a spring 188, engaging a pin 190 which projects from the side of the latch bar, to a position where the nose 192 of the bar will be engaged by one of the driving dogs 30 as a result of which 5 the jack carrier and the jack will be moved along the orbital track 52, 54. In order to disengage the latch bar from the driving dog there is provided at each station where it is desired that the jack shall stop a stop member 194 carried by a 10 slide 196 guided for vertical movement in a dovetail guideway formed in the face of the track rail 54 and the bracket by which it is supported. The stop member 194 has an inclined cam face 198 arranged to be engaged by a roll 200 on the 15 under side of the front end of the latch bar 186. It will be seen that when the roll 200 rides up the surface 198 the latch bar will be drawn forward to the position illustrated in Fig. 6 where it is disengaged from the driving dog 30 and, the 20 roll falling into a pocket 202 in the stop member 194, the jack carriage will be detained and held stationary until released.

Means is provided to permit the operator to release the latch bar 186 manually at will when 25 he is ready to permit the jack to be reconnected to the driving wheel and again moved along the track. This means comprises a hand lever 204 which is pivoted to the arm 50 at 206 and is pivotally connected to the slide 196 at 208. A spring 30 pressed plunger 210 in a rearward extension 212 of the lever 204 reacts against a stationary abutment 214 upon the arm 50, tending to hold the slide 196 elevated but permitting the said slide to be lowered by depressing the hand lever 204 35 until the stop 194 is moved below the roll 200, thereby disengaging the latter and permitting the spring 188 to snap the latch bar 186 rearward whereupon its nose 192 is almost immediately engaged by the next driving dog 30 to reach it and 40 the jack is moved along to the next station where it is automatically stopped unless, before reaching the next station, it collides with a preceding jack, in which case it is instantly disconnected from the driving dog 30 and comes to a stop. The 45 mechanism for effecting this disconnection will now be described.

Depending from the rear end of the latch bar 186 is a pin 216 (see Fig. 7) which is embraced by the forked end 218 of a lever 220 which is 50 pivoted at 222 to the under side of the carrier 56. The other end of the lever carries a roll 224 which is arranged to engage an inclined cam surface 226 (see Figs. 2 and 6) formed upon a trailing extension 228 of the carrier 56. By inspecting 55 Fig. 6 it will be seen that this engagement will occur and that the roll 224 will assume the position shown in broken lines in time to permit a following jack to be disconnected from the driving wheel before it does damage to the next jack in advance of itself with which it is about to collide. The swinging of the lever 220 resulting from the roll 224 riding upon the cam face 226 of the next jack causes the latch bar 186 to be disconnected from the driving dog 30 and held out of the path 60 of the latter until the next jack ahead is removed, whereupon the latch bar is again projected into the path of one of the driving dogs 30 and the travel of the jack is resumed.

Mechanism responsive to the travel of the jack 70 for automatically providing a follow-up pressure to compensate for yielding or contraction of the materials will now be described.

The upper portion of the pressure screw 156 is provided with elongated pinion teeth 230 which 75 are engaged by a gear segment 232 pinned to the

upper end of a vertical shaft 234 rotatable in bearings 236, 238 in the upright 150. To the lower end of the shaft 234 is pinned a ratchet wheel 249 which may be engaged by a pawl 242 pivoted at 244 to the outer end of a swinging arm 246 and pressed toward the ratchet wheel 240 by a spring 248. The arm 246 is loosely journaled upon the shaft 234 between the ratchet wheel and the bearing 238 and is normally swung back against an adjustable stop screw 250 by a spring 252 surrounding a guide rod 254 which is pivoted at 256 to the arm 246 and passes loosely through an opening in the upright 150. Another adjustable stop screw 258 is arranged to engage the pawl and throw it out of engagement with the teeth of the 15 ratchet wheel 240 when the arm 246 is all of the way back against the stop screw 250 but to permit the pawl to be engaged with the ratchet wheel by the spring 248 as soon as the arm 246 is swung in a counterclockwise direction as viewed in Fig. 8. 20

The shaft 234 is surrounded by torsion spring 260 which tends to turn it and the gear segment 232 in a clockwise direction, looking down, and, therefore, to unscrew the pressure screw 156. Since the spring 260 is relatively light this will 25 occur only when the pawl 242 is disengaged from the ratchet 240 and when no pressure is being applied to the work. This is merely for the purpose of restoring the presser foot 142 to its highest position after the work has been released 30 and the lever 178 thrown up.

When a jack, containing a shoe and heel clamped under pressure, moves along the track to a position where a roll 262 journaled upon the pivot pin 244 encounters the face 48 of one of 35 the stationary spider arms 42, 44, 46 the arm 246 will be swung about the axis of the shaft 234, causing the shaft to be rotated by the pawl and ratchet 242, 240 and, through the gear segment 232 and pinion 230, causing the pressure screw 40 156 to be turned down to apply a follow-up pressure to the work. Although the stationary spider is shown as having three arms, this number may be varied to produce the desired number of increments of follow-up pressure and the amount of 45 each such increment may be varied by adjustment of the stop screw 250.

Referring now to Figs. 9 and 10, the last 112 has in the interior of its heel seat portion a movable pressure plate 264 from which a rod 266 extends to the cone of the last, the said rod having a head 268 between which and the last is interposed a light spring 270 which tends to hold the pressure plate 264 down flush with the surrounding last heel plate 272. 55

Mounted in the last support 110 is a plunger 274 carrying a button 276 pressed upward by a relatively stiff spring 278 and normally projecting somewhat above the surface of the support 110. When the last is placed upon the last pin 114 60 the head 268 of the rod 266 will engage the button 276 and when downward pressure is applied to the shoe upon the last the pressure plate 264 will be forced against the interior of the heel seat portion of the insole of the shoe with a pressure 65 determined by the strength of spring 278. This aids in bringing the parts of the work firmly together over their entire areas.

In the illustrated machine four operating stations are provided and in Figs. 1 and 2 these have 70 been designated A, B, C and D, respectively. At station A there is provided mechanism for molding the heel seat of a shoe to conform to the cup of the heel to be attached thereto. This mechanism comprises an electrically heated molding die 75

280 pivotally supported in the forked end 282 of a hollow arm 284 provided with a handle 286 and arranged to slide longitudinally through a sleeve 288 connected by a universal joint to an arm 290. 5 The arm 290 is supported by a stationary bracket 292 bolted to the tracks 52, 54 and may swing in a horizontal plane about a vertically arranged pivot 294 which is surmounted by a table 296 upon which the die 280 may be placed when not 10 in use. Electric current for heating the die is conducted to it by a conductor 298 passing through the hollow arm 284 and the die is so designed that the presser foot 142 can be brought down on top of it to apply molding pressure to the heel 15 seat of the shoe.

The operation of the machine will now be described. A lasted shoe is first placed upon the last support 110 of the jack at station A and the back gage 124 is, if necessary, adjusted to the 20 shoe. The heated molding die is then positioned upon the heel seat of the shoe and the hand lever 178 is pulled down to apply pressure. If the pressure produced by the hand lever is insufficient to secure the desired molding effect it may be increased to any required degree by turning the hand wheel 160 which will rotate the pressure screw 156 and produce as heavy pressure as may be needed.

After the heel seat is sufficiently molded the 30 pressure is released and the heel seat molding die 280 is removed from the shoe and placed upon the table 296. The operator now depresses the handle 204, permitting the jack carrier to be connected by the driving wheel 26 and causing the jack to be moved along the track to station 35 B where it is automatically stopped by the stop member 194 at that station.

At station B an operator may apply a heel to the shoe with cement or other adhesive interposed between them, positioning the heel firmly 40 against the portion of the combination back gage 124 which projects above the shoe bottom. This operator will now repeat the pressure applying 45 operation, first pulling down the lever 178 to apply preliminary clamping pressure to the heel and shoe and then turning the hand wheel 160 to apply an increased final pressure. With the parts of the work securely clamped under pressure, this operator now depresses the handle 204 at station B releasing the jack and permitting 50 it to proceed, under the influence of the driving wheel 26, toward station C. Ordinarily, from the time the shoe and heel are placed under pressure at station B, the pressure is not released until 55 the jack has made the circuit of the track and arrived again at station A, where the pressure is released and the shoe, with the heel attached, removed. If, however, it is for any reason desired to release the pressure at any stage of 60 the journey of the jack around the track, this may be readily done and the pressure may thereafter be re-applied, if desired.

Each station is provided with a stop device 194 and if a jack is released at station B, for example, 65 before the jack at station C is released, it will merely move along to the position shown in broken lines in Fig. 2 and stop until the jack at station C is released and allowed to move on. This is true of any jack which encounters a stationary jack ahead of itself at any place in its 70 path of movement around the track.

The purpose of station C is to provide for rasping the joint between the heel breast and the shoe sole and applying cement to the heel breast 75 and breast flap, while station D is provided for

laying the breast flap upon the heel breast and rubbing it up. Obviously, an operator may be provided at each station or a single operator may pass from one station to another to perform the different operations. Moreover, if it be desired to omit some of the operations the stop elements 194 at one or more stations may be fastened down so that the jacks will not stop at these stations.

The track 52, 54 may be made as large as necessary to accommodate as many jacks as desired since each jack is separate from all the others and the number of jacks to be employed will be determined by the length of time it is desired that each shoe shall remain under pressure.

Having described the invention, what is claimed as new and desired to be secured by Letters Patent of the United States is:

1. In a heel attaching machine, the combination of a jack movable through a plurality of operating stations, means for moving the jack through said stations, means at one of said stations for molding the heel seat of a shoe upon the jack, means for detaining the jack at a succeeding station to permit a heel to be applied to the shoe, and means upon the jack for clamping the heel under pressure upon the molded heel seat.

2. In a heel attaching machine, the combination of a jack movable through a plurality of operating stations, means for moving the jack through said stations, means at one of said stations for molding the heel seat of a shoe upon the jack, means for detaining the jack at a succeeding station to permit a heel to be applied to the shoe, means upon the jack for clamping the heel under pressure upon the molded heel seat, and means at a subsequent station for increasing the clamping pressure.

3. In a heel attaching machine, the combination of a movable jack, means for moving the jack along a predetermined path, means for applying clamping pressure to a heel and shoe upon the jack, and follow-up means at a plurality of separated positions adjacent to said path for restoring or increasing said pressure from time to time as the jack is moved along the path.

4. In a heel attaching machine, the combination of a movable jack, means for moving the jack along a predetermined path, screw means for applying clamping pressure to a heel and shoe upon the jack, and means for automatically turning the pressure screw in the pressure increasing direction as the jack is moved along said predetermined path.

5. In a heel attaching machine, the combination of a movable jack, means for moving the jack along a predetermined path, screw means for applying clamping pressure to a heel and shoe upon the jack, pawl and ratchet means for turning the pressure screw in pressure increasing direction, and means for engaging and operating said pawl and ratchet means as the jack is moved along said predetermined path.

6. In a heel attaching machine, the combination of a last support, a presser foot for pressing a heel upon a lasted shoe upon said support, a pressure screw for actuating said presser foot, a worm gear engaging the screw and manually operable to move the screw rapidly lengthwise to apply preliminary pressure to the heel and shoe, means for locking the worm gear, manual means for turning the screw to provide increased final pressure, and automatic means for turning the screw further to provide follow-up pressure.

7. In a heel attaching machine, the combination of a jack base, a cradle pivotally mounted to

swing freely about an axis above and transverse to the jack base, a last support so positioned upon the cradle that said axis will substantially pass through the heel seat of a lasted shoe upon said support, a rigid back gage for the lasted shoe upon said cradle, and means for pressing a heel upon the shoe.

5. In a heel attaching machine, the combination of a last support, a presser foot for pressing

a heel upon a lasted shoe upon said support, a pressure screw for actuating said presser foot, a worm gear engaging the screw and operable to move the screw rapidly lengthwise to apply preliminary pressure to the heel and shoe, and means for turning the screw to provide increased final pressure.

5

JOHN T. LANCASTER.
